UNITED STATES PATENT OFFICE.

CARL LINDE, OF MUNICH, GERMANY.

METHOD OF UTILIZING LIQUID AIR IN EXPLOSION-MOTORS.

SPECIFICATION forming part of Letters Patent No. 664,958, dated January 1, 1901.

Application filed November 27, 1899. Serial No. 738,326. (No model.)

To all whom it may concern:

Be it known that I, CARL LINDE, doctor of philosophy, a subject of the King of Bavaria, residing at Munich, in the Kingdom of Bavaria, German Empire, have invented a new and useful Improvement in Methods of Utilizing Liquid Air in Explosion-Motors, of which the following is a specification.

Since it has been rendered possible to liquefy air in any desired quantity, it has often been suggested that liquid air should be used for driving motors. A careful investigation, however, shows that the energy expended in liquefying the air is so out of proportion to the energy obtained under the most favorable circumstances by the conversion of the liquefied air into the gaseous state, which while further expanding is utilized for doing work, that the idea of utilizing liquid air for driving motors can only be applied when the question of economy is not taken into consideration. This, however, is different when the liquid air is used in combination with a combustible in such a manner that the oxygen of said air is caused to act on the combustible under the high pressure resulting from its transition from the liquid into the gaseous state.

My invention may be embodied in a combustion-motor of the kind in which combustible materials—such as coal-gas, petroleum, benzene, or the like—are used for obtaining the driving power. It is well known that for the proper working of these motors the atmospheric air to be mixed with the fuel requires to be applied under a high pressure, which is produced by compressing the air in a special cylinder, and improvements in the said motors are mainly directed toward increasing the compression and working pressure generally. The effective work of the motor in this case is therefore the difference between the work done on the gas in its compression and the work performed by its expansion. Now by the use of liquid air the necessity for compressing the air in a special working cylinder in order to obtain increase of pressure by reduction of volume is obviated, as the pressure is produced by the transition of the air from the liquid into the gaseous state, this transition occurring in a closed space. Moreover, the compression, and con-

sequently the working pressure, can be greatly increased without necessitating mechanism more complicated than that already existing. 55 Accordingly it is possible to adopt very small dimensions, this being of special value where a motor of small weight and relatively high efficiency is required—as, for instance, in driving vehicles. 60

The accompanying drawing represents a diagrammatical arrangement of my improved motor.

The liquid air is kept under atmospheric pressure in the vessel *l*, which is well protected exteriorly against heat, from which vessel the said liquid air is drawn off by a feed-pump *p*, having a variable stroke. The actuation of the pump *p* is effected from the shaft *a* of the fly-wheel by means of a crank-gearing *f* and lever-gearing *g h*, the stroke of the pump being regulated by adjusting the lever-gearing. The pump supplies the liquid air to the conduit or serpentine *s*, the walls of which are not protected against the access 75 of heat, but are in direct contact with the atmosphere. Consequently the liquid air, entering the conduit at a temperature below 180° centigrade, is allowed to absorb heat, whereby it is caused to reassume the gaseous 80 state, the conduit being made in the form of a serpentine tube *a* to afford a large conducting-surface. From the said conduit the gaseified air enters a combustion-chamber *b*, into which at the same time is introduced the combustible material or motive fluid to an amount required for the power to be exerted. This material may consist of a liquid fuel and may be introduced by means of an apparatus *m*, similar to that generally employed for supplying lubricating material to the pistons of steam-engines. The piston, which is movable up and down in the apparatus, is set in motion from the shaft *a* of the fly-wheel by means of a belt-gearing *d* and worm-wheel *k* 95 in such a manner that on the piston moving downward the motive fluid is pressed from the apparatus *m* into the combustion-chamber *b*. The ignition can be effected in the manner usually adopted in explosion-engines. 100 In starting, an electric igniter may be used and afterward ignition may be effected by causing the combustible material to drop upon an asbestos body, which after being

rendered incandescent by the combustion is thereby kept in a state of incandescence. The combustion may also be obtained by bringing the liquid air directly together with the combustible material. This enables the gasifier or serpentine to be omitted; but the consumption of combustion material is increased thereby.

The combustion should always be caused to take place under such conditions as will prevent the resulting gases from having too high a temperature. This will easily be obtained by injecting a greater quantity of liquid air than is required for perfect combustion, as obviously the greater the injected volume of liquid air the lower the temperature at which the gasified air is allowed to meet the fuel. The combustion gases are then introduced into the working mechanism proper, which by preference may be a compound engine *e*, consisting at least of two cylinders in order to enable the gases, entering at a very high pressure in the first cylinder, to expand in a profitable manner. The effect may then be still further increased by the arrangement of a second combustion-chamber *c* between the cylinders in order to mix the gases with fuel and firing the mixture, so that the temperature of the gases, which has fallen by the expansion, is raised before entering the next following cylinder.

What I claim, and desire to secure by Letters Patent of the United States, is—

1. The method of utilizing liquid air in working explosion-motors which consists in intermittently gasifying liquid air, causing the gasified air to mix with fuel under the pressure resulting from its transition from the liquid to the gaseous state, firing the thus-obtained mixture of fuel and compressed air, and causing the products of combustion to act upon the piston, substantially as and for the purpose described.

2. The method of utilizing liquid air in working explosion-motors which consists in intermittently injecting liquid air, gasifying the same on its passage to the combustion-chamber, causing the gasified air to meet the fuel in the combustion-chamber under the pressure resulting from its transition from the liquid into gaseous state, firing the thus-ob-

tained mixture of fuel and compressed air, and causing the products of combustion to act upon the piston, substantially as described.

3. The method of utilizing liquid air in working explosion-motors which consists in intermittently injecting liquid air, gasifying the same by means of the atmospherical heat while passing to the combustion-chamber, causing the gasified air to meet the fuel under the pressure resulting from its transition from the liquid into the gaseous state, firing the thus-obtained mixture of fuel and compressed air, and causing the products of combustion to act upon the piston, substantially as described.

4. The method of utilizing liquid air in working explosion-motors which consists in intermittently injecting a quantity of liquid air greater than needed for burning a given quantity of fuel, gasifying the injected air on its passage to the combustion-chamber, causing the gasified air to meet the fuel under the pressure resulting from its transition from the liquid into the gaseous state, firing the thus-obtained mixture of fuel and surplus of compressed air, and causing the products of combustion and surplus of air to act upon the piston, substantially as described.

5. The method of utilizing liquid air in working explosion-motors which consists in intermittently injecting a quantity of liquid air greater than needed for burning a given quantity of fuel, gasifying the injected air on its passage to the fuel, causing the gasified air to meet the fuel under the pressure resulting from its transition from the liquid into the gaseous state, firing the thus-obtained mixture of fuel and surplus of compressed air, causing the products of combustion and surplus of air to act upon the piston, mixing said products and surplus of air with fuel, firing anew and causing the resulting products to act upon a second piston, substantially as described.

In testimony whereof I have hereunto set my hand in presence of two subscribing witnesses.

CARL LINDE.
